UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

PRINTING-PRESS.

No. 894,575.

Specification of Letters Patent.

Patented July 28, 1908.

Application filed July 5, 1907. Serial No. 382,320.

To all whom it may concern:

Be it known that I, HENRY F. BECHMAN, of Battle Creek, in the county of Calhoun and State of Michigan, have invented certain new and useful Improvements in Printing-Presses; and I hereby declare that the following is a full, clear, and exact description thereof, reference being had to the accompanying drawings, which form part of this specification.

The present invention relates to new and useful improvements in web perfecting printing presses, and more particularly to that type embodying a reciprocating type bed and coöperating impression cylinder.

The primary object of the invention is to provide a novel construction which permits the web to be fed continuously through the press at a uniform speed, thereby obviating the necessity for employing an equalizer or compensating device, which latter is for many reasons objectionable since the web frequently becomes slack with the result that the paper strikes in different positions and considerable offset is occasioned.

For a full understanding of the invention and the merits thereof and also to acquire a knowledge of the details of construction, reference is to be had to the following description and accompanying drawings, in which—

Figure 1 is a longitudinal sectional diagrammatic view of a printing press embodying the invention, the said press being shown as comprising but a single pair of printing couples. Fig. 2 is a similar view showing a slightly modified form of press which comprises two pairs of printing couples. Fig. 3 is an enlarged detail view illustrating one mechanism for throwing the impression cylinders off and on impression.

Corresponding and like parts are referred to in the following description and all the views of the drawings by like reference characters.

A printing press embodying the present invention consists essentially of a plurality of printing couples and means for threading a web through the same, each of the said couples comprising a reciprocating type bed and a stationary co-acting impression cylinder.

The press may either be built with a single pair of printing couples as shown in Fig. 1, or with a plurality of pairs of the printing

couples, according to the extent and nature of the work to be performed.

Any approved means may be employed for lifting the impression cylinders into an inoperative position when the type beds are upon their return movement.

Specifically describing the construction shown in Fig. 1 it will be observed that the same is formed with a pair of reciprocating type beds 1 and 2 arranged one above the other in approximately horizontal and parallel planes, and stationary co-acting impression cylinders 1^a and 2^a. The cylinder 2^a operates only on the forward (right hand) stroke of the bed 2; while the cylinder 1^a operates only on the return (left hand) stroke of the bed 1. These beds are moved at a uniform speed during impressions, corresponding with the travel or feed and delivery of the web. The press shown in Fig. 1 can be used to print and perfect alternate sheets or lengths of web, or the printing couples in Fig. 1 can print alternate spaces on opposite sides of the web. The web W is drawn from the roll R and passes around the guide roller 3, thence extending upwardly between the feed rollers 4 and 5 and downwardly around the guide roller 6 after encircling the upper portion of the last mentioned feed roller 5. It is obvious that feeding and delivering systems are not absolutely necessary in this press, as the paper passes through the machine at a uniform rate of speed corresponding with the uniform speed of travel of the beds, but in a press where compensating devices are used it is necessary to have in-feeding and delivering systems. If found desirable a coaxter tape such as that indicated at 7 may be utilized to facilitate the passage of the web between the feed rollers and in the present instance the coaxter tape is shown as passing around the feed roller 4 and the two idlers 8, 8. From here the web passes over the guide roller 9, down and between the cylinder 2^a and reciprocating type bed 2, up and around the guide roller 10, over and around the coaxter roller 11, up and around the coaxter roller 12, back and around the guide roller 13, down and between the impression cylinder 1^a and reciprocating type bed 1, up and over the guide roller 14. The web is then drawn over and around the roller 15, and up and around the delivery roller 16 whence it passes to any approved form of cut-

ting and assembling mechanism. A coaxer tape 17 is shown as coöperating with the delivery roller 16 to facilitate the passage of the web.

5 In the construction shown in Fig. 2 four printing couples are employed comprising the reciprocating type beds 1^a, 2^a, 3^a and 4^a; and the co-acting stationary impression cylinders 1^b, 2^b, 3^b and 4^b, the said printing 10 couples being arranged in pairs and the type beds of each pair being disposed in horizontal and approximately parallel planes. In this press cylinders 2^b 4^b are arranged to print only on the forward stroke of beds 2^a 4^a; 15 and cylinders 1^b 3^b print only on the return stroke of beds 1^a 3^a. If cylinders 2^b 4^b and 1^b 3^b be arranged to print alternate spaces of the web perfected papers can be produced. The web W' is drawn from the roll R' and 20 passes around the guide roller 3^c, up and between the feed rollers 4^c and 5^c, down and around the guide roller 6^c, over and around the guide 9^c, down and between the reciprocating type bed 2^a and impression cylinder 25 2^b, up and around the guide roller 10^c, under the roller 11^c, around the guide roller 18, between the type bed 4^a and cylinder 4^b, up and around the guide roller 19, and around the coaxer roller 20. From here the web W' 30 extends up and around the upper coaxer roller 21, back and around the guide roller 22, down and between the type bed 3^a and co-acting impression cylinder 3^b, up and around the guide roller 23, over the roller 12^c, around 35 the guide roller 13^c, down and between the type bed 1^a and impression cylinder 1^b, up and around the guide roller 14^c, over and around the roller 15^c, and up and around the delivery roller 16^c and thence to any approved 40 cutting and assembling mechanism.

It will be observed that coaxer tapes similar to those described in connection with the construction shown in Fig. 1 are employed to assist the web in its passage around the 45 feed roller 5^c and the delivery roller 16^c.

Any suitable means such as the well known Napier movements may be employed to impart a uniform reciprocating movement to the type beds and in the present instance 50 each of the beds is shown as provided with an upper rack 24 and a lower rack 25, the said racks alternately meshing with a pinion 26. This pinion 26 is keyed upon the same shaft as a gear wheel 27 which meshes with 55 an intermediate gear wheel 28 rigid with a gear wheel 29 which engages a gear wheel 30 serving to drive the impression cylinder of the corresponding couple. It is within the province of the invention to drive all the rollers in the press at a uniform speed equal to 60 the speed of the web or to merely use them as idlers. In the former instance it will be perfectly obvious however that there will be less offset and smutting of the paper after being printed.

The superposed cylinders may be thrown on and off impression by the mechanism illustrated in Fig. 3. As therein shown the upper and lower cylinders are respectively journaled in eccentric boxes a, a', which are 70 connected by levers b, b', to a common bar c, which depends below the lower bed and is provided with a friction roller c' engaging a race cam groove d' in or attached to a gear d, journaled on a stud or shaft d', and meshing 75 with a gear e driven by the gear 29 of the lower bed actuating mechanism. The cam d' is driven at such speed as to raise and lower the bar c once for each reciprocation of the beds, and the eccentrics a, a', are so 80 set that one cylinder can be thrown on impression as the other is thrown off.

Having thus described the invention, what I claim as new and desire to secure by Letters Patent is:

1. In a printing press, the combination of 85 a pair of parallel type beds one above the other, and an impression cylinder co-acting with each bed, means for reciprocating the beds and moving them at uniform speed of 90 travel during the taking of impression, means for throwing off impression on alternate strokes of the bed, means for directing a web successively between the beds and cylinders, and means for continuously feeding the web 95 forward between the beds and cylinders both during and after the taking of impressions.

2. In a web printing-press, the combination of two reciprocating beds and co-acting cylinders arranged one above the other, 100 means for throwing the cylinders alternately off impression during one stroke of the beds, means for moving the beds at a uniform speed of travel during the taking of impression, said beds and cylinders printing alternately, and means for continuously feeding the web 105 between the beds and cylinders both during and after the taking of impressions.

3. In a web printing press, the combination of two reciprocating parallel beds and 110 co-acting cylinders arranged in different planes, means for throwing off impression during one stroke of the beds, means for moving the beds at a uniform speed of travel during their printing strokes, means for feeding a web between said beds and cylinders, said beds and cylinders printing alternately 115 and only when the respective beds are moving in the direction of the lead of the web, and means for continuously feeding the web 120 between the beds and cylinders both during and after the taking of impressions.

4. In a printing press, the combination of 125 a pair of type beds arranged in parallel planes one above the other, and a pair of impression cylinders co-acting with said beds, means for reciprocating the beds and causing them to move at a uniform speed of travel during the taking of impressions, said beds and cylinders printing alternately and only when the co- 130

acting bed is moving in the direction of the lead of the web, and means for feeding a web continuously and at uniform speed between the beds and cylinders.

- 5 5. In a web printing press, the combination of two beds and two co-acting cylinders arranged in one plane; two other beds and two co-acting cylinders arranged in a plane above and parallel with that of the lower beds and cylinders; means for reciprocating the beds and moving them at a uniform speed of travel during the taking of impressions, the lower beds and cylinders printing on the forward stroke of the beds, and the upper beds and cylinders printing on the return stroke of the beds, and means for directing a web successively between the beds and cylinders.
- 10 6. In a web printing press, the combination of two reciprocating beds and co-acting cylinders arranged in one plane, two other

beds and two co-acting cylinders arranged in a plane above and parallel with that of the lower beds and cylinders, means for moving all the beds at a uniform speed of travel during the taking of impressions, the lower beds and cylinders operating in alternation with the upper beds and cylinders, and the lower beds and cylinders printing on the forward stroke of the beds, and the upper beds and cylinders printing on the return stroke of the beds; and means for feeding a web successively between the beds and cylinders at a speed uniform with that of the travel of the beds during impressions.

In testimony that I claim the foregoing as my own, I affix my signature in presence of two witnesses.
